L. E. COHOON

TOILET CONSTRUCTION

Filed Feb. 12, 1926

FIG. 2.

Inventor
Luther E. Cohoon
By Arthur W. Nelson
Atty.

UNITED STATES PATENT OFFICE.

LUTHER E. COHOON, OF LA GRANGE, ILLINOIS.

TOILET CONSTRUCTION.

Application filed February 12, 1926. Serial No. 37,741.

This invention relates to improvements in toilet constructions and it consists of the matters hereinafter described and more particularly pointed out in the appended 5 claims.

The primary object of the invention is to provide a simple and efficient means which operates at all times to ventilate and aerate a toilet bowl by causing the flow of a current of air through and out of the same to a vent leading to atmosphere thus removing from the bowl such odors as are normally attendant therein.

A further object of the invention is to 15 provide a bowl of the kind, with a combined flushing and ventilating rim, whereby odors are drawn into the rim to be delivered to a vent or stack leading to atmosphere, whereby the bowl is maintained in a sanitary condition, even though the usual seat and cover 20 are in their closed position.

These objects of the invention, as well as others together with the many advantages thereof, will more fully appear as I proceed 25 with my specification.

In the drawings:

Fig. 1 is a view in side elevation of a 30 toilet bowl embodying my invention, together with an associated flush tank. Fig. 2 is a detail vertical section on an enlarged scale through one portion of the bowl rim as taken on the line 2—2 of Fig. 1.

Fig. 3 is another detail vertical section on an enlarged scale as taken on the line 3—3 35 of Fig. 1.

Referring now in detail to that embodiment of the invention illustrated in the accompanying drawing, 1 indicates a toilet bowl and 2 indicates a "low down" flush tank 40 associated therewith, which as shown herein is supported upon one surface of a hollow building wall 3 as by means of brackets 4. The bowl may be of any of the modern types and includes a bowl body 5, a base flange 6 by which it is secured to the floor 6^a and a 45 top rim 7. As the connection between said bowl and the usual soil pipe forms no particular part of the present invention, it is neither shown or described herein. The 50 bowl is provided with the usual hinged seat 8 and cover 9, each having the usual bumper buttons 10 and 11 by which the seat is spaced a short distance above the bowl and the cover is spaced a short distance above the seat, 55 when said seat and cover are in a closed position.

The rim as shown herein is of a combined flushing and ventilating type although the invention is also applicable to bowls of other flushing types, but the invention will be described as of the combined type above mentioned. The rim 7 is tubular in cross section and as shown is substantially rectangular and includes a channel 12 defined by inner and outer walls 7^a and 7^b and top and bottom walls 7^c and 7^d respectively, the body wall 5 joining the bottom wall of the rim about midway between the inner and outer walls thereof as best shown in Fig. 2.

The bottom wall 7^d of the rim is so formed 70 as to permit a discharge of flushing water from the interior or channel of the rim to the interior of the bowl. As shown herein, said bottom wall includes a plurality of discharge openings 13 arranged near the body 75 wall 5, but as is apparent an equivalent means such as a slit (not shown) may be used in place thereof without departing from the spirit of the invention. In the inner wall 7^a of the rim near its top margin is 80 provided a plurality of ventilating openings 14 and preferably said openings are inclined 85 upwardly from the interior of the bowl toward the interior or channel of the rim so as to bring those ends of said openings communicating with the channel as high as possible above the water therein when the bowl is being flushed.

At the rear of the bowl, the rim is provided with an extension 15 in which is fixed 90 one end of a combined vent and flushing conduit 16. The other end of said conduit is connected to the horizontal end of an elbow 17 located in the building wall 3, the vertical leg of said elbow receiving the bottom end of a vent pipe 18 which opens to atmosphere in any suitable manner. The flush tank 2 has a bottom discharge conduit 19 which opens through one side of the conduit 16 and at the bottom thereof as best shown in Fig. 3. 100 As shown in said figure, the flush tank conduit is of a diameter smaller than that of said conduit 16 so that even though water is passing through the conduit 19 into the conduit 16, the latter is at no time filled thereby 105 nor is the channel 12, so that the bowl is vented even during the flushing thereof. By reason of channel construction of the bowl rim, and its connection to the vent or stack 18, air is drawn from the interior of the 11 bowl into the rim channel 12 through the openings 14 and from said rear channel

through the conduit 16 and the elbow 17 to the vent or stack 18. Thus a current of air is established which acts to withdraw all odors from the bowl, up the vent to atmosphere so that the bowl is aerated and maintained in a sanitary and odorless condition. Even though the cover and seat be in their closed position, air may enter the bowl, through the spaces between bowl and seat and seat and cover, so that at all times a ventilating and aerating action takes place within the bowl.

As will be apparent, my improved construction while simple is indeed efficient for its intended purpose, and while in describing the same I have referred in detail to the form and arrangement of the various parts thereof, the same is to be considered as by way of illustration only, so that I do not wish to be limited thereto except as may be pointed out in the appended claims.

I claim as my invention:

1. A toilet bowl including a bowl body and a hollow rim, having a single chamber therein, said rim having inner and outer side walls and top and bottom walls, there being a set of openings in said bottom wall adjacent the bowl body and a second set of openings in the inner wall of said rim above said first mentioned set of openings, both sets of openings communicating with the single chamber in said rim.

2. A toilet construction comprising a bowl, the rim of which is hollow to provide a single chamber therein of a depth sufficient to accommodate the flushing water and at the same time to provide an air space above the level of said water, there being suitable water discharge openings in the bottom wall portion of the rim for the discharge of water and a plurality of openings in the side wall portion of the rim above said water level, the said rim being adapted to be connected to a flushing water supply and to a vent pipe.

3. A toilet construction comprising a bowl, the rim of which is hollow to provide a single chamber therein of a depth sufficient to accommodate the flushing water and at the same time to provide an air space above the level of the water, there being suitable water discharge openings in the bottom wall portion of the rim for the discharge of water and a plurality of openings in the side wall portion of the rim above said water level, said last mentioned set of openings being inclined downwardly toward the interior of the bowl, a fitting of substantially large diameter connecting said rim to a vent and a second fitting connecting the first with a source of flushing water supply.

In testimony whereof, I have hereunto set my hand, this 10th day of February, 1926.

LUTHER E. COHOON.
